UNITED STATES PATENT OFFICE.

FRANK S. BLAKESLEY, OF ROCKFORD, ILLINOIS, ASSIGNOR OF ONE-HALF
TO THE WEYBURN & BRIGGS COMPANY, OF SAME PLACE.

TWYER-IRON.

SPECIFICATION forming part of Letters Patent No. 619,010, dated February 7, 1899.

Application filed February 24, 1898. Serial No. 671,518. (No model.)

To all whom it may concern:

Be it known that I, FRANK S. BLAKESLEY, a citizen of the United States, residing at Rockford, in the county of Winnebago and State of Illinois, have invented certain new and useful 5 Improvements in Twyer-Irons, of which the following is a specification.

The object of this invention is to produce a twyer-iron in which the volume of the air- 10 blast from the bellows or blower to the fire may be varied at pleasure and which when set will not readily be disarranged by jars or 15 blows.

In the accompanying drawings, Figure 1 is 15 a vertical central section through the twyer-iron on the central line of the air-blast pipe. Fig. 2 is also a vertical central section through the twyer-iron, but on the central line of the 20 tube which incases the rod for the air-valve. Fig. 3 is a plan view looking into the fire-pot 25 of the twyer-iron.

Like letters of reference indicate corresponding parts throughout the several views.

A is the fire-pot of the twyer-iron. 25 A' is the air-chamber beneath the fire-pot. B is the air-blast pipe for conducting the blast from the bellows or blower to the air-chamber A'. 30 C is the pipe or tube for incasing the rod for the air-valve.

C' is a pivoted shutter for closing the end 35 of the pipe C.

D is the rod for the air-valve. The outer end of this rod is provided with the ring or 40 eye D', and the inner end D² thereof is made square in cross-section.

E is a ring for the bottom of the fire-pot, having the depending lugs E' to provide bearings for the inner end of the valve-rod D.

45 F is the valve-closure having a square central opening for the reception of the square end D² of the valve-rod D. The form of the closure is similar to that of a ball with portions cut away, leaving facet-like surfaces, which in the closure are to provide for the passage of the air-blast. The square end D² of the valve-rod does not pass through the closure exactly on the axial center of the ball, but a little to one side thereof, in order that 50 the closure shall balance in any position and

not be possessed of the tendency to turn when shaken or jarred.

The lower angle of the air-chamber A', opposite the air-blast pipe B, is filled in, providing a deflecting-surface for turning the 55 air-blast upward.

In operation my twyer-iron is set into a forge in the usual manner, the pipe C extending outward at the side of the forge. The pipe B is connected with the air-blast and the 60 fire started. The volume of the air-blast is altered by turning the valve-closure F so that any one of its three different facets permits the passage of the air-blast into the fire. The position of the parts shown in Fig. 1 indicates 65 the air-valve as closed. In Figs. 2 and 3 it is represented as being open. The closure F is heavy enough so as not to be turned by the force of the air-blast and therefore may be set in any desired position and the blast 70 regulated accordingly.

When it is desirable to clear the air-chamber A' of the ash and cinders which must necessarily fall into it, the ring E is removed, the valve-rod D withdrawn through the outer 75 end of the pipe C, and the closure F taken from the air-chamber A', when the latter may be cleared of all cinders. The parts are easily replaced preparatory to building a fire in the fire-pot. 80

I claim as my invention—

1. In a twyer-iron, in combination, a fire-pot, an air-chamber, an air-blast pipe opening into the air-chamber, a ring adapted to be set into the lower part of the fire-pot which 85 ring has two depending perforated lugs, a rotatable closure for varying the volume of the air-blast to the fire-pot, having facets of different sizes also having a pivotal opening eccentric to its center and a rod extending through such opening and through the perforations of the lugs, for rotating the closure, substantially as and for the purpose specified.

2. In a twyer-iron, in combination, a fire-pot, an air-chamber, having an inclined air-deflecting wall, an air-blast pipe opening into the air-chamber, a ring adapted to be set into the lower part of the fire-pot which ring has two depending perforated lugs, a rotatable closure for varying the volume of the air-blast 100.

to the fire-pot, having facets of different sizes also having a pivotal opening eccentric to its center, a rod extending through such opening and through the perforations of the lugs for 5 rotating the closure, and a pipe for incasing the rod, substantially as and for the purpose specified.

3. In a twyer-iron, in combination, a fire-pot, an air-chamber having an inclined air- 10 deflecting wall, an air-blast pipe opening into the air-chamber, a ring adapted to be set into the lower part of the fire-pot which ring has two depending perforated lugs, a rotatable closure for varying the volume of the air-blast

having facets of different sizes also having an 15 angular pivotal opening eccentric to its center, a rod for rotating the air-closure extending through the perforations of the lugs and adapted to fit and extend through the pivotal opening through the closure, a pipe for incasing 20 the rod and a pivoted shutter for closing the outer end of the pipe about the rod, substantially as and for the purpose specified.

FRANK S. BLAKESLEY.
